UNITED STATES PATENT OFFICE.

GEORGE W. CILLEY, OF NORWICH, CONNECTICUT.

FASTENING DEVICE FOR GUN-BARRELS.

SPECIFICATION forming part of Letters Patent No. 450,448, dated April 14, 1891.

Application filed November 28, 1890. Serial No. 372,933. (No model.)

To all whom it may concern:

Be it known that I, GEORGE W. CILLEY, of 5
Norwich, in the county of New London and
State of Connecticut, have invented certain
new and useful Improvements in Fastening
Devices for Gun-Barrels, of which the following,
taken in connection with the accompanying
drawings, is a specification.

My invention relates to the method of fast-
ening a gun-barrel to its breech-frame; and
it consists in fitting into the frame at one
side of the gun a jaw or clamp adapted to
enter into a transverse groove made in the
barrel and to be drawn into place by a clamp-
ing-screw operated from the other side of the
gun. This mechanism and arrangement is
shown in the accompanying drawings, in
which—

Figure 1 is a side view of a part of a gun,
showing a part of my attachment. Fig. 2 is
a side view similar to Fig. 1, but taken from
the other side. Fig. 3 is a cross-section taken
on line *x x* of Figs. 1 and 2. Fig. 4 is a view
in cross-section showing the clamping-jaw
slightly modified. Fig. 5 is a plan showing
a part of the gun and indicating by dotted
lines the shape of the modified clamp of Fig. 4.

In the drawings I have shown only such
parts of a gun as are necessary to illustrate
my invention, and need not describe the gun
in detail, as my device will apply equally
well to a great many styles of guns.

The barrel is indicated by A and the breech-
frame by B. The breech end of the barrel B
is coned, as indicated by dotted lines at *a a*,
Figs. 1 and 5, and fits into a corresponding
recess made in the breech-frame.

C, Fig. 3, is a cone-shaped clamping-piece
adapted to be moved laterally in relation to the
gun-barrel and to fit into a transverse recess
made in the barrel, as indicated, and thus to
hold the barrel firmly in its place when desired.
The clamping-piece C is moved in and out
by the screw D, said screw D having a hand
or arm H extending from it, as shown. By
turning the screw D in one direction the

clamping-piece C is drawn in, so that it will
hold the barrel firmly in place. When it is
desired to remove the barrel, the screw D is
so turned as to force the clamping-piece C 50
outward, as indicated by dotted lines in Fig.
2. This causes the clamping-piece C to with-
draw from the recess in the gun-barrel, and
thus leave it in condition to be removed from
the frame. The clamping-piece C is held 55
from turning and also limited in its motion
by the screw K, which fits in a groove made
in the clamping-piece for that purpose. The
screw D is held longitudinally in place by
the pin E, Fig. 3, which fits into an annular 60
groove made in it, as shown.

In Figs. 4 and 5 the clamping-piece is modi-
fied in shape, it being provided with an arm
C' extending upward through a vertical
groove made in the side of the barrel, as 65
shown. It also has a short projection C² ex-
tending below its center, which forms, in con-
nection with the screw K, a guide for keep-
ing it in place and limiting its movement.
The front side of the arm C' is beveled, as 70
shown at *c c*, Fig. 5, so that as the clamping-
piece is drawn in it will act as a wedge to
force the gun-barrel back firmly into its place.

I claim—

In a gun, the combination of a barrel hav- 75
ing a cone-shaped breech end, said breech
end adapted to fit into a recess in the breech-
frame and having a lateral groove for receiv-
ing a clamping-piece, as described, said clamp-
ing-piece so located in the said breech-frame 80
that it can engage with and hold the barrel in
place, and a screw by which the said clamp
is operated, substantially as and for the pur-
pose set forth.

In testimony whereof I have signed my 85
name to this specification, in the presence of
two subscribing witnesses, on this 24th day
of November, A. D. 1890.

GEORGE W. CILLEY.
